UNITED STATES PATENT OFFICE

172,105

WOMAN'S PROTECTIVE GARMENT

Frances M. Nowell, Los Angeles, Calif.

Application October 28, 1952, Serial No. 22,016

Term of patent 14 years

(Cl. D3—26)

To all whom it may concern:

Be it known that I, Frances M. Nowell, a citizen of the United States and resident of Los Angeles, county of Los Angeles, State of California, have invented a new, original, and ornamental Design for a Woman's Protective Garment, of which the following is a specification, reference being had to the accompanying drawing, forming a part hereof, in which:

Fig. 1 is a perspective view of a woman's protective garment, showing my new design;

Fig. 2 is a front view; and

Fig. 3 is a rear view.

I claim:

The ornamental design for a woman's protective garment, substantially as shown.
